CLAIM

The ornamental design for a juice dispenser assembly, as shown and described.

DESCRIPTION

FIG. 1 is an exploded top perspective view of my new design for a juice dispenser assembly, shown with a first lid and second lid separated from the jug for clarity of disclosure; FIG. 2 is an exploded bottom perspective view thereof; FIG. 3 is an exploded front elevational view thereof; FIG. 4 is an exploded rear elevational view thereof; FIG. 5 is an exploded left side elevational view thereof; FIG. 6 is an exploded right side elevational view thereof; FIG. 7 is an exploded top plan view thereof; FIG. 8 is an exploded bottom plan view thereof; FIG. 9 is a top perspective view of my new design for a juice dispenser assembly shown in isolation with a first lid attached to a jug in a closed configuration; and, FIG. 10 is a top perspective view of my new design for a juice dispenser assembly shown in isolation with a second lid attached to a jug in a closed configuration.

The dash-dash broken lines in the drawings depict portions of the juice dispenser assembly that form no part of the claimed design.
